SPORT SHORTS

William R. S. MacRae, Sydney, New South Wales,
Australia, and Arthur R. Kneibler, Kenosha,
Wis., assignors to Cooper's Incorporated,
Kenosha, Wis., a corporation of Wisconsin

Application September 10, 1949, Serial No. 114,970

3 Claims. (Cl. 2—228)

1

This invention relates to an improved form of shorts suitable for wear as an outer garment when participating in various sports such as swimming, golfing, hiking, or the like, and more particularly to shorts that provide the wearer with body support, the amount of which may be adjusted independently of the disposition of the waistline of the outer portion of the garment.

It is therefore an object of this invention to provide an improved form of such shorts which are designed particularly for men's use, although not restricted thereto; to provide such a garment which incorporates a pair of outer trunks and a relatively independent inner garment, the front portion of the waistline of which is independently adjustable with respect to the front portion of the waistline of the outer trunks; to provide shorts comprising a pair of outer trunks and a relatively independent inner garment, the latter being preferably removably secured to said outer trunks so that it may be quickly and easily removed for drying separately, if desired, or for washing or replacement with another similar inner garment; to provide a garment which is exceptionally comfortable and which always presents a neat, trim line at the point of contact of the outer trunks and the abdomen of the wearer.

Further objects and advantages of this invention will become evident as the description proceeds and from an examination of the accompanying drawings which illustrate one embodiment of the invention and in which similar numerals refer to similar parts throughout the several views.

In the drawings:

Figure 1 is a view in front elevation of one form of garment embodying the invention;

Figure 2 is a view in vertical cross-section taken along the line 2—2 of Figure 1, illustrating the relative disposition of the outer trunks and the inner garment;

Figure 3 is a sectional view of the garment shown in Figure 1, viewing the shorts from the front and illustrating the disposition of the inner garment within the outer trunks; and

Figure 4 is an enlarged cross-sectional view taken along the line 4—4 of Figure 3, illustrating a type of fastening device which may be utilized to secure the inner garment to the outer trunks.

Referring now to Figures 1, 2 and 3, the garment indicated generally by the numeral 10 may be made up of a pair of outer trunks 12 of substantially conventional design and appearance, and an independent inner garment 14 similar to legless underdrawers. The upper edge 16 of the

rear portion of the inner garment 14 is preferably removably secured to the rear portion 18 of the outer trunks 12 substantially parallel and in spaced relation below the upper edge 20 of the outer trunks. Suitable holding means may be provided for this purpose such as, for example, the snap fasteners 22, which are best shown in Figures 3 and 4. It is obvious, of course, that if desired, these snap fasteners may be eliminated and the upper edge of the rear portion of the inner garment united to the rear portion of the outer trunks, as described, by appropriately stitching the two component parts together along the upper edge 16 of the inner garment.

15 It should be noted that only the rear half of the inner garment is so secured to the corresponding rear half of the outer trunks, so that the front upper edge of the inner garment 24 freely extends across the inner side 26 of the front upper edge 28 of the outer trunks. This unsecured portion of the upper edge of the inner garment may be formed of a band of suitable elastic material 30, which band has a length that is normally less than the length of the corresponding portion of the upper edge 28 of the outer trunks 12, as best shown in Figure 2. Any other suitable means for constricting this unsecured portion of the waistband of the inner garment may be used. It might even be found desirable to utilize a draw-string for this purpose.

20 The outer trunks 12 may incorporate any suitable means adapted to constrict the waistline and to hold the trunks in place on the wearer. For example, the trunks may have a channel 32 formed in the upper edge thereof which channel is adapted to receive a belt member 34. The two slits 36 and 38 may be provided in the outer wall of the channel 32 at the front of the trunks, as shown in Figure 1, so that the two ends of the belt member 34 may extend out of the channel and be brought into cooperative holding relation after the garment has been properly placed on the body of the wearer. This belt member 34 thus serves to support the outer trunks 12 on the 25 waist of the wearer and these supported trunks, in turn, give support to the rear portion 16 of the inner garment 14.

30 Obviously other means could be utilized for this purpose, such as an attached half-belt in the front with a shirred elastic waistband in back, or it perhaps might be desirable to have the entire waistband formed of elastic material, as is the case in the so-called "boxer" type shorts.

35 Regardless of the exact type of construction utilized for the waistband of the outer trunks,

the disposition of the rear upper edge 16 of the inner garment 14 is determined primarily by the disposition of the rear upper edge 20 of the outer trunks 12. However, as previously mentioned, the front upper edge 24 of the inner garment 14 is independent of the front upper edge 28 of the outer trunks and its disposition is therefore determined independently of the placement of the front upper edge 28 of the trunks 12. This feature, coupled with the fact that the upper edge of the inner garment is secured in spaced relation below the rear upper edge 20 of the trunks, permits the wearer to determine the degree of support he wishes to have from the inner garment by appropriately adjusting the front upper edge 24 thereof and the elastic band 30. Two possible alternative positions of this edge 24 are shown by the dotted lines in Figure 2. This feature results in the preservation of a trim line at the front upper edge 28 of the outer trunks at all times, in spite of possible variations in the disposition of the front upper edge 24 of the inner garment.

In other words, for a particular disposition of the waistline of the outer trunks 12 which provides the best appearance, the upper edge 24 of the inner garment 14 may be disposed over a fairly wide vertical range so that the wearer may select the degree of support which he wishes to obtain from the inner garment and still maintain the outer trunks 12 in the preferable position.

The outer trunks 12 may be made of any desirable material, which may vary depending upon the particular sport or sports for which the garment in question is designed. The inner garment, however, is preferably made of a suitable knitted material and may have a construction which is designed to provide adequate support and a snug fit without binding or bunching, by forming the garment of a plurality of pieces having their wales extending in predetermined directions to give them a resiliently conforming relation to the anatomy of the wearer, as is disclosed, for example, in U. S. Patent No. 2,012,879 issued August 27, 1935 to Arthur R. Kneibler, one of the present applicants.

It will thus be seen that a garment which incorporates this invention provides a different basic circumference at the waistline between the outer trunks and the inner garment, with the inner garment being provided with an elastic band member across the front thereof to insure a snug fit and appropriate support. This inner garment is also appropriately disposed with relation to the outer trunks so that an adjustability in the amount of support provided by the former is available whereas, at the same time, the outer trunks can be worn with their waist properly located for comfort and neat appearance without having to undergo the displacement effected for the inner garment, incident to the support adjustment.

The drawings and the above discussion are not intended to represent the only possible forms of this invention, in regard to details of construction. Changes in form and in the proportion of parts, as well as the substitution of equivalents are contemplated, as circumstances may suggest or render expedient, without departing from the

spirit or scope of this invention as further defined in the following claims.

What is claimed is:

1. A garment of the character described comprising outer trunks, means adapted to constrict the waistline of said trunks and to support said outer trunks from the waist of the wearer, an inner garment made of knitted material adapted to give support to the wearer, said inner garment being formed of a plurality of knitted pieces, the wales of which extend in directions such that said pieces have a resiliently conforming relation to the anatomy of the wearer and yet provide adequate support therefor, the upper edge of the rear portion of said inner garment being secured to the rear portion of said outer trunks substantially parallel and in spaced relation to the rear upper edge of said trunks, an elastic waistband at the front upper edge of said inner garment of lesser length than the front upper edge of the unconstricted waistline of said trunks, said elastic waistband of said inner garment being capable of being positioned on the wearer independently of said waistline of said trunks so as to enable the wearer to select the degree of support desired from said inner garment.

2. A garment of the character described comprising outer trunks, means adapted to constrict the waistline of said trunks and to support said outer trunks from the waist of the wearer, an inner garment made of knitted material, the wales of which are disposed so that said inner garment is relatively inextensible in a direction substantially normal to the waistline thereof and so that said inner garment gives support to the wearer, the upper edge of the rear portion of said inner garment being secured to the rear portion of said outer trunks substantially parallel and in spaced relation to the rear upper edge of said trunks, an elastic waistband at the front upper edge of said inner garment of lesser length than the front upper edge of the unconstricted waistline of said trunks, said elastic waistband of said inner garment being capable of being positioned on the wearer independently of said waistline of said trunks so as to enable the wearer to select the degree of support desired from said inner garment.

3. A garment of the character described in claim 2, further characterized in that said upper edge of the rear portion of the inner garment is removably secured to the rear portion of said outer trunks.
